ELECTRON DISCHARGE DEVICE

Peter C. Goldmark, Brooklyn, N. Y., assignor to
 Markia Corporation, New York, N. Y., a corporation of New York

Application April 24, 1936, Serial No. 76,112

4 Claims. (Cl. 250—27.5)

This invention relates to electron discharge devices and particularly to electron discharge devices which have a composite envelope partly of vitreous material and partly of metal.

5 The invention has for its object the provision of a device of the character described with an improved construction and arrangement of parts whereby the same may be readily and economically manufactured.

10 More specifically, an object of the invention is to provide an electron discharge device with an evacuated envelope composed of vitreous portions and of metallic portions which are joined together with a sealing substance that effects 15 a hermetical seal and has such a low vapor pressure that the vacuum within is not liable to deteriorate substantially over relatively long periods.

Still another object is to provide an electron 20 discharge device having a composite envelope and an electrode arrangement adapted to discharge electrons in a beam against a wall with an improved window for observing the discharge effect without distortion.

25 Still another object is to provide an improved construction for a cathode ray tube which may be made in relatively large sizes at relatively small expense and has an evacuated envelope constructed partly of metal and partly of vitreous members.

Other objects of the invention will in part be obvious and will in part appear hereinafter.

The invention accordingly comprises the features of construction, combination of elements, 35 and arrangement of parts, which will be exemplified in the construction hereinafter set forth, and the scope of the invention will be indicated in the claims.

For a fuller understanding of the nature and 40 objects of the invention, reference should be had to the following detailed description taken in connection with the accompanying drawing, in which:

Fig. 1 is a longitudinal sectional view through 45 a cathode ray tube having a composite envelope constructed in accordance with the invention;

Fig. 2 is a front elevation illustrating the nature of the seal about the window member of the cathode ray tube shown in Fig. 1;

50 Fig. 3 is an enlarged cross-sectional view showing the nature of the seal between the window member and the metal member shown in Fig. 2;

Fig. 4 is a similar fragmentary view showing 55 the seal between the metal member and the

tubular vitreous member comprising the envelope shown in Fig. 1; and

Fig. 5 is a fragmentary view showing a modified form of seal provided for the window member.

Referring now to the drawing, and particularly to Fig. 1, 10 denotes a vitreous tubular member which has a closed reentrant end portion 11 in which are sealed the conductors of a heated cathode element 12. Adjacent the cathode is 10 disposed an anode element 13 which is adapted to cooperate with the cathode element to provide an electron gun projecting a beam of electrons that will impinge upon a window member provided as hereinafter described. Suitable deflector plates 14 for the beam may also be sealed 15 in this portion of the device when desired.

Joined to the member 10 is a metallic member 15, this member being somewhat funnel-shaped and having its smaller end recessed, as indicated 20 at 16, to provide an annular groove for receiving the open end of the vitreous member 10. The joint thus provided is sealed by inserting in the groove about the vitreous member a suitable sealing substance, as shown at 16' and herein- 25 after more fully described. The interior portions of the member 15 which overlie the edge of the member 10 are preferably fluted or grooved to provide fingers, as indicated at 17 in Fig. 4, in order the better to accommodate expansion and 30 contraction at the joint.

The metal member 15 while indicated as being 35 preferably funnel-shaped may, of course, have any desired shape, the larger end being here shown as formed with a generally rectangular contour terminating in a recessed or grooved flange 18. About the inner side of the flange is a shoulder 19 adapted to support an inserted vitreous member 20, which is preferably transparent or translucent and designed to serve as a 40 window. Thus inserted member has a groove 21 formed about its edge for cooperating with the groove in the flange 18 and receiving the inserted sealing substance, as shown at 21', which 45 may be of the same character as that inserted at 16'. In order to serve as a cathode ray tube adapted for oscillographic or television purposes, this window member may have an interior coating of a suitable fluorescent substance, such as willemite or zinc sulphide, the presence of which 50 is indicated on the window at 22.

A modified form of the flange on the metallic member 15 adapted for sealing purposes is shown in Fig. 5. Here, the flange member proper is 55 shown at 18' and indicated as made as a sepa-

rate ring that is welded to the body of the metallic member denoted 15'. The inserted window member is indicated at 20' and has a beveled edge which is adapted to cooperate with the V-shaped groove formed in the flange ring 18', the sealing substance being inserted in substantially the same manner as before.

The sealing substance of the present invention is preferably a substance that is initially 10 plastic and dries hard at normal temperatures to become firmly formed in place and adheres to both metal and vitreous materials, such as glass, transparent phenolic condensation products and other suitable plastics, which may be employed 15 for the vitreous members. Certain equi-molecular mixtures of relatively complex organic constituents of low volatility are found to have the desired adhering characteristic and are suitable. For example, a mixture of ethylene glycol 20 with phthalic anhydride, when taken in such proportions as to provide a substantially equi-molecular composition, is satisfactory because of the plastic qualities and the relatively low vapor pressure which such mixture has. The mixture 25 is made by taking substantially 1 part by weight of ethylene glycol to 2.4 parts by weight of phthalic anhydride; the desired consistency of the sealing substance being achieved by first mixing these constituents and then heating at a 30 relatively high temperature for a relatively long period, for example, at 180° C. for 24 hours. The resulting substance is plastic and may be inserted when at a temperature of 100° C. This substance also dries at 60° C., and when cold, 35 dry and permanently in place, has a normal vapor pressure that is of the order of 10⁻⁵ mm. of mercury.

In the event that the sealing substance becomes too dry after preparation but before insertion, it may be moistened by mixing with it 40 a small portion of tricresyl phosphate; for example, the softening agent may be taken as 1 part in 200 of sealing substance.

Another sealing substance which may be employed 45 comprises a mixture of powdered urea with furfuraldehyde. These constituents are also preferably taken in such proportions that the resulting mixture is substantially equi-molecular.

A cathode ray tube may be manufactured in accordance with the present invention by providing a glass member, such as shown at 10, with the desired electrode parts. This is then heated and while hot, a metal member 15 and 50 a window member 20 are put in place and the sealing material inserted to close the joints. The tube or device is, at this period, placed upon the pumps and evacuated while the parts are hot, the application of heat being kept up during the 55 entire period of the pumping, if desired, by placing the device in a suitable oven. When the pumping is completed, the device is sealed off in the ordinary manner, a suitable getter (not shown in the interests of clearness of illustration in the drawing) being employed when it is desired to obtain a vacuum of a relatively high order.

From the construction employed, it is seen that 70 window members of substantially any size and configuration may readily be provided; for example, for cathode ray tubes for use in television, a large, substantially plane viewing screen may be provided, of sufficient thickness to resist atmospheric pressure regardless of the 75 degree of vacuum within the tube. The window

member may be formed also to give desired optical effects, all undesired distortion, due to curvature in the window, being avoided by the use of independent insertable vitreous members of the character indicated.

Cathode ray tubes in which the electrodes are mounted in a metal member are thus feasible for use, the only vitreous part required being the window member, which may be inserted as provided by the invention.

The sealing substance when permanently in place in the joint about the window member is seen to project laterally both against the groove of the metal member and against the groove of the window member, whereby there is a wedging 15 action which effectually stops any tendency for relative motion between the edge of the window member and the metal groove 18 when pressure is applied to the face of the window member. The seal, once formed by the adherence of the 20 sealing substance to both the metal and vitreous member, is thus self-preserving and is not liable to deterioration through usage.

It will be also understood that, because of the 25 relatively low vapor pressure of the sealing substance, the vacuum within the device is not liable to substantial deterioration over relatively long periods, thereby providing a device of the character indicated having a relatively long life.

Since certain changes may be made in the 30 above construction and different embodiments of the invention could be made without departing from the scope thereof, it is intended that all matter contained in the above description or shown in the accompanying drawing shall be interpreted as illustrative and not in a limiting 35 sense.

Having described my invention, what I claim as new and desire to secure by Letters Patent is:

1. In an electron discharge device, the combination with electrode elements adapted to serve as cathode and anode, of an evacuated hermetically-sealed envelope comprising a vitreous member and a metal member having a joint in the form of a groove for receiving an edge of 45 said vitreous member, and a sealing substance in said groove cooperating with said edge to close said joint consisting of a substantially equi-molecular mixture of ethylene glycol and phthalic anhydride which is adapted to be inserted while 50 relatively hot and which dries at substantially 60° C. and has a vapor pressure when permanently in place that is in an order of 10⁻⁵ mm. of mercury.

2. In an electron discharge device, the combination with electrode elements adapted to serve as cathode and anode, of an evacuated hermetically-sealed envelope comprising a vitreous member and a metal member having a joint in the form of a groove for receiving an edge of said 60 vitreous member, and a sealing substance in said groove cooperating with said edge to close said joint consisting of a substantially equi-molecular mixture of powdered urea and furfuraldehyde which when permanently in place adheres 65 to both metal and the vitreous member and has a relatively low vapor pressure.

3. In a cathode ray tube, the combination with a tubular glass member closed at one end and provided with electrode elements adapted to 70 serve as cathode and anode, of a metal member having one end recessed to provide an annular groove for receiving the open end of said tubular member, a groove formed on the other end of said metallic member and provided with a 75

supporting shoulder, a vitreous window member disposed in said groove on said shoulder, and a sealing substance in both said annular groove and said window supporting member groove cooperating with the edges of said inserted members to close the joints and of a character when permanently in place which has a relatively low vapor pressure.

4. In a vacuum cathode ray tube, in combination, an envelope member having a metallic tubular portion provided with a supporting shoulder at the window end and an axially projecting

annular ring around said shoulder, a vitreous window member supported on said shoulder, said window member being smaller than the ring, whereby the window member may be readily positioned on said shoulder, the ring and the edge 5 of the window member being so shaped as to provide an annular space therebetween at least part of which decreases in cross-section toward the said shoulder, and a sealing substance in said 10 annular space adapted to hermetically seal the window member to the metallic tubular portion.

PETER C. GOLDMARK.
